SCREEN

Charles V. Hallenbeck, Denver, Colo.

Application August 9, 1932, Serial No. 628,015

8 Claims. (Cl. 209—326)

This invention relates to sizing screens, its principal object being to provide a screening-element of novel construction by which the constituents of gravels, sands and other materials may be accurately and completely separated according to their sizes by a simple gyratory action.

Another object is to provide in apparatus of this character, an adjustable resilient element which expedites the separative action upon material under treatment and which may be adjusted to vary said action in accordance with the nature of the material.

A further object is to provide in conjunction with the screen-element, means to deliver the separated sizes, in regulatable quantities, and still other objects reside in details of construction and in novel arrangements and combinations of parts as will be clearly brought out in the course of the following description.

In the accompanying drawings, in the several views of which like parts are similarly designated,

Figure 1 is a partially broken plan view of an apparatus embodying the distinctive features of the present invention,

Figure 2 is a vertical section taken on the line 2—2 of Figure 1,

Figure 3 is a sectional elevation of the screening-element of the apparatus showing a modified method of supporting and operating the same,

Figure 4 is a fragmentary section in the plane indicated by the line 4—4 in Figure 2 and drawn to a larger scale, and

Figures 5 and 6 are outline views of the screening-element, showing different methods of supporting the same, to effect movement of the material under treatment in different directions.

The screening-element above referred to comprises a preferable rectangular box 5 containing three screens 6, 7 and 8 of differing meshes. The screens extend between the sides of the box and from an end of the same toward the opposite end from which they are spaced at different lengths in order to discharge their respective oversizes and undersizes separate from each other. The screen-box slants toward its discharge end and it is movably supported at an end by a shaft 9 adapted to impart a gyratory movement to the box, and at its opposite end by a pair of leaf-springs 10.

The shaft which is mounted for rotation in boxes 12 projecting from a cross-bar 13 of a supporting frame 14 of suitable construction, has, as best shown in Figure 4, two eccentric parts 15, each carrying one of two component members of ball bearings, as at 16.

The opposite members 17 of the ball bearings are fastened inside a tube 18 which by means of brackets 19 is secured at the upper end of the screen-box. The tube is to this end provided with flanged heads 20 to which the brackets are fastened by means of bolts 21. Two series of balls 22 engaging in grooves of the members of the ball bearings by which the tube is mounted upon the eccentrics of the shaft, provide for a substantially frictionless movement of the eccentrics relative to the tube.

In order to exclude dirt and dust from the bearings, the ends of the tube are closed by means of retaining rings 23 engaging the respective members 17 of the ball-bearings, closure plates 24 partially spaced from the respective rings, and packings 25 of suitable material held between the rings and the plates, in engagement with the respective eccentrics. Bolts 26 connect the ring and the plate at each end of the tube with the heads 20 of the same.

It will be apparent that by rotation of the shaft, a lengthwise gyratory motion is imparted to the screen box. This motion is yieldingly opposed by the two leaf springs at the opposite ends of the box and it is a distinctive feature of the invention that the springs are adjustable so as to vary the effect of the gyratory motion of the box upon material supported by the screens thereof.

The multiple plate leaf springs are for this purpose provided at their lower ends with semi-circular feet 27 which rest in correspondingly formed chairs 28 on the supporting frame of the apparatus. Bolts 29 secure the ends of the springs in their adjusted positions on the frame, and it will be readily apparent that by loosening the bolts, the ends of the springs may be turned in the seats of the chairs whereby to vary the angularity of the springs relative to the perpendicular. The upper ends of the springs are pivotally connected at the sides of the box, as at 30, and the springs are bent to be continually under tension.

In the operation of the screening-element, the gravel, sand or other material is fed upon the upper or coarser screen 6 which is longer than the others. The vibratory motion of the box causes the undersize of the material to fall through the meshes of the screen 6 upon the next following screen 7 which is of intermediate mesh and which is shorter than the upper one, while the oversize is moved toward and across the free end of the screen. The lowermost screen 8 is of finest mesh and is shorter than the intermediate screen, and in the operation the under-

size of the material on the intermediate screen falls upon the finest or lower screen 8, where a third undersize is sifted from the material, while the oversizes of both the intermediate and lower screens move toward and across the free ends of the screens.

5 A chute 31 divided into two compartments, 32 and 33, by a partition 34, conveys the oversizes discharged from the screens 7 and 8 into receiver 35, and the oversize of the upper screen and the undersize of the lower screen fall into the same receiver at opposite sides of the chute. The lower end portions of the sides of the chute and of the partition 34, divide the interior of the receiver 10 into separated compartments.

The receiver has in its bottom, openings separately connected with the compartments, which may be closed by suitable gates 36 and it is to be understood that by proper manipulation of the 20 gates, the various sizes of the material contained in the receiver, may be discharged in any desired proportions as may be required in preparing a mix for road-surfacing or other constructive or engineering work.

25 As stated hereinbefore, the action of the gyroscopic motion of the screen-box upon the material on the several screens thereof, may be varied by adjustment of the springs 10. The larger the 30 angle of the spring is with relation to the perpendicular, the more severe the action will be upon the material. If the springs slant at a comparative small angle from the perpendicular, as for example, in the construction shown in the drawings, the material will be subjected to a 35 comparatively mild or sifting action, but by increasing the angle, the screening action becomes more severe and it causes a more vigorous up and downward movement of the particles in the material, resulting in a beating or concussive 40 movement which tends to break up clods in the material and separate the particles of gummy or sticky substances.

It will thus be seen that by simple adjustment 45 of the springs the machine is readily adapted for sizing materials of different characters and conditions, either dry or wet.

When, in the operation, the screen box is gyrated by rotation of the eccentrics, its spring-supported end moves in an arc of which each 50 spring is a radius. As stated hereinbefore, the springs are connected under tension so that they will be pulling against the eccentrics at all times. It is preferred not to pass the rest point of the 55 springs in the movement of the screen box, but have all the tension of the springs in one direction in order that the eccentrics may be under pressure at all times, thereby preventing "whipping" of the eccentrics.

In the modified construction illustrated in 60 Figure 3, the screen-box is supported at both ends by means of tensioned leaf-springs 37 and 38 and the reciprocating motion of the box is effected through the instrumentality of two pitmen 39 which connect with the eccentrics on the shaft 9. The two pairs of springs may be in parallel relation to each other as shown in the drawings, or 65 they may be adjusted to extend at different angles relative to the perpendicular to still further vary the action of the movement of the box upon 70 the material passing over the screens thereof.

When the springs are adjusted to different 75 angles, either the lengths of the pitmen 39 must be changed or the position of the chairs 28 must be varied. The first stated expedient has been shown in the drawings, in which the pitmen are

composed of two lapping sections connected by bolts 39a in slots 39c.

Instead of supporting the box upon the springs, it may be suspended from the same as has been shown at 40 in Figure 5, and by reversing the angle of inclination of the springs relative to the perpendicular passing through their fixed ends, as shown in Figure 6, the material may be caused to move in the opposite direction, or as indicated by the arrow, toward the upper end of the box. Under this condition the screens are arranged so that their free ends are spaced from the upper end of the box, to deliver the various sizes separately into the receiver as before.

80 Other changes in the construction and arrangement of the several parts and elements comprised in the apparatus may be resorted to without departing from the spirit of the invention as herein defined.

85 What I claim and desire to secure by Letters Patent is:

1. Apparatus of the character described, comprising a screen-box, a continuously tensioned leaf spring supporting the box at an end thereof, the opposite end of the spring being mounted for 100 rotary adjustment thereof, and mechanism to impart a gyroscopic movement to the box.

2. Apparatus of the character described, comprising a screen-box, a leaf-spring inclined from the perpendicular and supporting the box at an 105 end thereof, the mounting for the other end of the spring, adapted for rotary adjustment to vary the angle of inclination of the same, and mechanism to impart a gyroscopic movement to the box.

110 3. Apparatus of the character described, comprising a screen-box, an inclined leaf-spring supported at one end for rotary adjustment to vary its angle of inclination relative to the perpendicular, and pivotally connected with the box, at 115 its opposite end, and means to impart a gyroscopic movement to the box.

4. Apparatus of the character described, comprising a screen-box, a leaf-spring pivotally connected at one end, with the box and having an 120 arcuate foot at its opposite end, a relatively stationary chair supporting the foot for rotary adjustment, means for fixing the foot in adjusted positions, and mechanism for imparting a vibratory movement to the box.

125 5. Apparatus of the character described, comprising a screen-box, leaf-springs inclined from the perpendicular and supporting the box at its ends, means for rotatably adjusting said springs and holding them at selective angles relative to 130 the perpendicular, and mechanism to impart a vibratory movement to the box, including a pitman adjustable to vary the intensity of said movement.

135 6. Apparatus of the character described, comprising a screen-box, leaf-springs inclined from the perpendicular and supporting the box at its ends, means for rotatably adjusting said springs and for holding the springs at selective angles relative to the perpendicular, and mechanism to 140 impart a vibratory movement to the box, including a pitman pivotally connected to the box and adjustable to vary the intensity of said movement.

145 7. Apparatus of the character described comprising a screen-box, mechanism at an end of the screen-box to impart a reciprocating movement thereto, and a pivoted, permanently tensioned spring slanting from the perpendicular 150

and supporting the end of the screen-box remote from said mechanism, the opposite end of the spring being mounted for rotary movement thereof.

5 8. Apparatus of the character described comprising a screen box, a continuously tensioned leaf spring supporting the box at one end there-

of, the opposite end of the spring being mounted for rotary adjustment thereof, and mechanism adjacent the opposite end of said box and co-operative with said spring to impart a gyratory movement to the box.
